Patented Dec. 11, 1917.

FIG. 1

FIG. 2

FIG. 3

INVENTOR.

George Lawrence Smith,
BY Clifford S. Dunn
ATTORNEY

UNITED STATES PATENT OFFICE.

GEORGE LAWRENCE SMITH, OF LONDON, ENGLAND.

FIRE AND TEMPERATURE ALARM.

1,249,842.

Specification of Letters Patent. Patented Dec. 11, 1917.

Application filed December 4, 1915. Serial No. 64,978.

To all whom it may concern:

Be it known that I, GEORGE LAWRENCE SMITH, a subject of the King of Great Britain, residing in London, England, have invented certain new and useful Improvements in Fire and Temperature Alarms, of which the following is a specification.

My invention relates to alarms of the so-called "rate of rise" type, in which the 10 alarm is initiated through the expansion of air contained in a small-bore metal tube passing through the protected zone and communicating with pressure-responsive means for transmitting a signal upon the occurrence of any sudden and unusual increase of pneumatic pressure within the tube. Such an alarm is illustrated and described in my United States Letters Patent No. 850,681, granted April 16, 1907. In that 15 patent I set forth that the tube, which communicates at one end with the detector, must be effectively closed at the other end, and as the simplest form of such structure I illustrated and described a tube in which the 20 end remote from the detector was actually sealed. I have discovered that this effective closure of the end of the tube remote from the detector is in some instances not necessarily an actual sealing of the tube, but may 25 be accomplished in a variety of ways without departing from the beneficial mode of 30 operation described in my prior Patent No. 850,681.

My present invention is directed to certain 35 other means of effecting the closure of the remote end of the tube, as will appear more fully below.

In the accompanying drawings, which 40 form a part of this specification, Figure 1 is a diagrammatic view of a room equipped with my improved fire or temperature alarm system. Fig. 2 is a view showing the detector in elevation and a modified closure for the remote end of the tube. Fig. 3 is a side 45 elevation of the detector shown in Fig. 2 in connection with a further modified form of closure for the far end of the tube.

Referring to the drawings in detail, the 50 numeral 1 designates the detector tubing extending through the area to be protected or supervised by the alarm. This tubing is preferably constructed of metal having a reasonably high thermal conductivity, such as copper, and may have an outside diameter of one-tenth of an inch with a bore of 55 one-twentieth of an inch, although these di-

mensions may be increased or decreased both as regards the diameter and the bore, to suit special conditions. The tubing is arranged in the protected zone in the manner described in my prior Patent No. 850,681 and terminates at one end in a detector 2, which need not be described in detail, since the detector illustrated and described in my prior patent is satisfactory for use in this connection.

Instead of sealing the far end 3 of the tubing, that is, the end remote from the detector, I find that it is, in many cases, satisfactory to continue the tubing for a considerable distance beyond the point 3 where it would naturally end in case it were hermetically sealed. The extreme end 4 of the tubing is then left open to the atmosphere. Owing to the small bore of the tubing used, 75 the added length, diametrically illustrated as extending from 3 to 4 in Fig. 1, is such that the skin or internal friction of the confined air against the tube is sufficient to prevent the sudden and unusual increase in 80 pressure generated in the main portion of the tube 1 by a fire or abnormal temperature condition within the protected zone, from being dissipated by leakage past the end 4 to an extent sufficient to prevent the transmission of an alarm. At the same time, 85 while this internal or skin friction acts as an effective closure for the far end of the tube, so that the operation of the system is in other respects identical with the mode 90 of operation described in my prior patent, still there are certain added benefits in special instances arising from leaving the extreme end 4 of the tube open to the atmosphere. For example, in all systems of this 95 general type, it is necessary to provide a leak, as described in my former patent, for permitting a compensation and balancing of the pressures between atmospheric pressure and that within the tube, resulting from 100 normal changes in temperature and changes in barometric pressure. The closure, which is constituted by the extra length of tubing 3-4 may, under some conditions, be used 105 to afford this regulated leak, or may be used in conjunction with a leak such as I have shown in my former patent, thus being an auxiliary to it and providing a regulated leak or means for regulating the leak at each end of the tube.

In Fig. 2 I have illustrated a somewhat modified form of device in which the length

of the tubing 3—4 is coiled up. This coiling of the tubing increases the internal or skin friction, and, therefore, the length of tubing which needs to be added to the normal installation to act as the effective closure for the far end of the tube, is less than the length which is required in the case of straight runs of tubing 3—4, such as shown in Fig. 1.

10 In Fig. 3 I have shown a further modification in which to the end 3 of the main stretch of tubing is added a short length of tubing 5 of decreased bore. Since the skin friction increases with decrease in diameter 15 of the tubing, it will be obvious that the length which it is necessary to add to constitute the effective closure of the remote end of the tubing, is much smaller when tubing of a reduced diameter is employed.

20 It will thus be seen that in all three modifications which I have illustrated the principle of operation is identical with that of the apparatus illustrated, described and claimed in my prior patent, one end of the 25 tubing in each case entering the detector and the remote end being effectively closed.

While I have illustrated and described only certain embodiments of my invention I realize that it is capable of wide adaptation without departing from the spirit of the invention of my prior Patent No. 30 850,681, and I do not desire to be limited to the precise construction shown and described herein.

35 Having thus described my invention, I claim:

1. In a fire and temperature alarm in combination, a metal tube of small diameter having a correspondingly small bore con-

taining air, a closed chamber, the interior of which communicates with the bore of the tube, said tube having a predetermined effective area, means operated by a sudden and unusual increase of pneumatic pressure in the effective area of the tube and in the chamber, for initiating an alarm, and means for compensating for a slow rate of temperature rise, said latter means consisting of an extension of said tube beyond its normally effective area.

2. In a fire and temperature alarm in combination, a metal tube of small diameter having a correspondingly small bore containing air, a closed chamber, the interior of which communicates with the bore of the tube, and means operated by a sudden and unusual increase of pneumatic pressure in the tube and chamber for initiating an alarm, a portion of the tube remote from said chamber being of reduced bore and open 60 to the atmosphere, but effectively closed against the dissipation of any sudden and unusual increase of pneumatic pressure within the intermediate portion of the tube.

3. In a fire and temperature alarm the combination, of a chamber, a small metal tube having a correspondingly small bore communicating therewith and having a predetermined normally effective area, means embodied within said chamber and adapted 70 to be operated by the sudden expansion of air in said tube to initiate an alarm, said tube being extended beyond this normally effective area to compensate for the gradual expansion of the air therein under the normal variations in the atmospheric temperature.

GEORGE LAWRENCE SMITH.
